[57] CLAIM

The ornamental design for a doll carriage, as shown and described.

DESCRIPTION

FIG. 1 is a top, front and side perspective view of a doll carriage showing my new design;

FIG. 2 is a side perspective view thereof;

FIG. 3 is a front perspective view thereof; and

FIG. 4 is a rear perspective view thereof.

The side opposite that shown in FIG. 2 is the mirror image thereof.

FIG.1

FIG.2

FIG. 3

FIG. 4
